US0D1033312S

(12) **United States Design Patent** (10) Patent No.: **US D1,033,312 S**
(45) Date of Patent: ** Jul. 2, 2024

(54) **HUB CONNECTING DEVICE STEM**

- (71) Applicant: **WARN Automotive, LLC**, Milwaukie, OR (US)
- (72) Inventors: **Russell Conine**, Portland, OR (US); **Craig Feusse**, Fenton, MI (US)
- (73) Assignee: **WARN Automotive, LLC**, Milwaukie, OR (US)

(**) Term: **15 Years**

(21) Appl. No.: **29/816,557**

(22) Filed: **Nov. 23, 2021**

(51) LOC (14) Cl. **12-16**
(52) U.S. Cl.
USPC **D12/207**

CLAIM

The ornamental design for a hub connecting device stem, as shown and described.

DESCRIPTION

FIG. 1 is a front perspective view of our hub connecting device stem.

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a back perspective view thereof.

The broken lines illustrate portions of the hub connecting device stem and form no part of the claimed design.

1 Claim, 8 Drawing Sheets
